UNITED STATES PATENT OFFICE.

HANS ADELMANN, OF NEW YORK, N. Y., ASSIGNOR TO HAM BOILER CORP., OF NEW YORK, N. Y., A CORPORATION OF NEW YORK.

HAM BOILER.

Application filed June 22, 1921. Serial No. 479,582.

To all whom it may concern:

Be it known that I, HANS ADELMANN, a citizen of Germany, residing at the city of New York, borough of the Bronx, in the 5 county of Bronx and State of New York, have invented certain new and useful Improvements in Ham Boilers, of which the following is a specification.

This invention relates to cooking appliances or apparatus and has particular reference to boilers or cookers for hams or other pieces of meat or for the cooking of meat loaves or the like, the invention relating to devices in a general way of the nature 10 set forth in Letters Patent of the United States No. 1272883 issued on my application to Ham Boiler Corp. on the 16th day of July, 1918.

Among the objects of the present invention is to improve devices of the character 20 indicated along the lines of simplicity of construction, cheapness of manufacture, and general satisfaction in practice.

More definitely stated whereas the boilers 25 of this type heretofore have generally included a receptacle and a cover between which there is provided relative resiliency during the cooking operation to provide for the swelling of the meat while cooking, in the 30 present case the receptacle and cover when connected have a practically rigid relationship, and resiliency is provided within the bottom of the receptacle by the employment of a false bottom resiliently mounted upon 35 the main bottom of the receptacle.

With the foregoing and other objects in view the invention consists in the arrangement and combination of parts hereinafter described and claimed, and while the invention 40 is not restricted to the exact details of construction disclosed or suggested herein, still for the purpose of illustrating a practical embodiment thereof reference is had to the accompanying drawings, in which like reference characters designate the same parts in the several views, and in which—

Figure 1 is a vertical longitudinal section of a preferred embodiment of the invention.

Fig. 2 is a plan view.

Fig. 3 is a fragmentary and elevational detail.

Fig. 4 is a vertical longitudinal sectional view indicating a modification.

Fig. 5 is a detail elevation of a part in Fig. 4.

Referring now more specifically to the drawings, 10 indicates the receptacle or main portion of the boiler which is or may be substantially similar in design and construction to that set forth in detail in my co-pending application for hand operated ham boilers, Serial No. 442,177, filed February 3, 1921. As set forth the receptacle has a substantially flat bottom 11 and vertical side and end walls, although in plan the shape of the boiler is oval so as to approximate somewhat the natural shape of the ham which is presumed to be fitted thereinto for boiling and which when cooked is adapted to be sliced into practically square or rectangular slices transversely from one end to the other. The receptacle is provided at its opposite ends with vertical series of rack teeth 12 projecting outward and downward.

The cover comprises a plate 13 which is substantially flat and is so shaped as to fit slidably within the upper portion of the receptacle so as to place the ham or other commodity under a suitable degree of pressure. To lock the cover in pressure applying position the end portions thereof are provided with upwardly projecting standards 14 each terminating in an outwardly directed goose neck 15, to the eye of which is pivoted a rigid hook 16 co-operating with the teeth of the rack beneath it. The standard and hook are long enough for proper co-operation with any portion of the rack teeth and yet permit the plate of the cover to extend well downward into the receptacle. Thus the cover may be made as a single casting or drop forging with the standards integral with the flat plate, and it is therefore very easy to make and also easy to manipulate and keep in a sanitary condition. When the hooks are interlocked with the selected teeth of the racks 12 the cover is held in a fixed position relative to the receptacle. As indicated in Fig. 3 the standards 14 have broad or fan shaped bases 14' so as to give great bracing strength without adding materially to the mass of the cover, the thick-

ness of the material being substantially uniform throughout the flat and standard portions.

It being borne in mind that in order to prevent loss or waste during the cooking operation incident to the expressing of the natural juices from the meat, provision must be made to allow for a certain amount of expansion of the meat, in the present instance I provide a false bottom comprising a plate 17 of any suitable material or thickness and upon which the bottom portion of the commodity being cooked will rest. This plate 17 is shown flat and supported by resilient means adapting the false bottom plate to move downward coincident with the swelling of the meat. As indicated there are three coil springs 18 arranged one at the small end of the boiler and two at the larger end. I also indicate two leaf springs 19 arranged lengthwise of the bottom and approximately parallel to each other. These several spring members may be attached either to the bottom 11 of the receptacle or to the false bottom plate 17, preferably the latter so that when the false bottom is removed the springs will remain attached thereto. The flat springs are shown connected to the plate 17 by means of rivets 20, and the coil springs may be attached by rivets, staples, or any other suitable means such as loops 21 struck from the plate 17. Either type of springs may be used to the exclusion of the other, and the invention contemplates other forms of cushions than the particular ones illustrated.

As shown in Fig. 4, while the lid 13 and standards 14 may be substantially the same as set forth in Fig. 1, I show a means to provide resiliency for the device interposed between the standards and the rack portions 12 of the receptacle. In this form of the invention the false bottom may not be used.

Each hook 16', which may be pivoted as above stated to the goose neck 15, comprises several relatively movable parts, the knuckle part 22 and the catch part 23. A spring 24 is anchored at its ends to the knuckle and the catch and tends to draw the catch toward the knuckle. These springs 24 are strong enough for their purpose of giving sufficient compression to the meat for shaping it and yet will allow sufficient expansion of the meat during cooking to prevent expressing therefrom the valuable ingredients thereof, as already explained.

As a suitable means for holding the catch member in proper operative position whereby its tooth 25 will always properly co-operate with a selected tooth of the rack 12, I show a pair of guide rods 26 fastened in an off-set portion 22' of the knuckle and extending thence downward parallel to each other and through the catch member and along which the catch member is slidable.

To the lower ends of the guide rods are attached adjustable stop means such as a plate 27 adjustable vertically along the rods as by means of nuts 28 threaded upon the rods. The plate 27 will prevent an excessive amount of strain being brought upon the spring 24, but for ordinary practice the catch will not impinge against the stop plate. Each catch member is provided with a lug or shank 23' through which pressure may be brought to bear downward thereupon for attaching the catch to the rack or detaching it therefrom. The rod structure 26 will constitute sufficient stiffness for the hook member as a whole to render the same equivalent to the hooks 16 of Fig. 1 so far as the co-operation with the rack teeth is concerned, but the catch member will nevertheless move freely lengthwise of the rods to afford the resiliency demanded.

It will be noted, furthermore, that in both forms of this invention the hook pivots are located far enough beyond the vertical plane of the racks to provide that the hooks will swing clear of the rack teeth by gravity when the lid or cover is depressed, and that the hooks are made to engage with the rack teeth by being forced inward.

I claim:

1. In a ham boiler, the combination with a receptacle constituting a mold for a ham or the like, of a cover fitted slidably within the receptacle for compressing the ham, said cover being provided with upwardly projecting standards, the upper ends of which extend outward beyond the upper edge of the receptacle, and engagement means for the receptacle pivoted to and depending from the outwardly projecting portions of the standards, the engagement members comprising hooks, each of which includes a knuckle pivoted to a standard, a catch member spaced below and movable relatively to the knuckle, and connecting means between the knuckle and the catch member providing for movement of the catch member resiliently with respect to the knuckle.

2. In a ham boiler, the combination with a receptacle having rack teeth and a cover slidable within the receptacle, of locking means between the cover and the receptacle comprising a pair of hooks flexibly connected to the cover and co-operating with the rack teeth, each hook comprising a knuckle connected by a horizontal pivot to a part of the cover, rigid guide means extending downward from the knuckle, a catch member movable along the guide means but held stiff thereby in other directions, and a spring anchored to the knuckle and the catch member, and tending to draw the catch member upward toward the knuckle.

3. In a ham boiler, the combination with a receptacle having rack teeth and a cover slidably movable within the receptacle, of

locking means between the cover and the receptacle comprising a pair of hooks flexibly connected to the cover and co-operating with the rack teeth, each hook comprising a pivoted knuckle, a pair of spaced parallel guide rods connected thereto and extending downward therefrom, adjustable stop means on the lower ends of said rods, a catch

member slidable along the rods but held thereby from movement in other directions relatively, and a coil spring having its ends anchored to the knuckle and the catch member respectively and located between said guide rods.

In testimony whereof I affix my signature.
HANS ADELMANN.
